UNITED STATES PATENT OFFICE.

NATHANIEL KING AND RICHARD A. ASHTON, OF FITCHBURG, MASSACHUSETTS, AS-
SIGNORS TO SENECA FALLS MACHINE COMPANY, OF FITCHBURG, MASSACHUSETTS.

BACK SQUARING ATTACHMENT FOR LATHES.

Application filed June 30, 1924. Serial No. 723,105.

This invention relates to engine lathes and is used particularly for turning and squaring-up work at several different points in its length. These operations are desirably performed at the back side of the machine at the same time that other turning operations are being performed at the front side of the machine.

It is the general object of our invention to improve the construction heretofore used for such purposes, particularly by providing for more convenient operation of the mechanism.

With these general objects in view, important features of our invention relate to the provision of a tool supporting slide, in combination with improved mechanism for automatically advancing and thereafter retracting the tool slide relative to the work; to the provision of means for moving the tool slide at high or low speed as required and for automatically varying the speed; to the provision of mechanism for simultaneously actuating two opposed tool slides; to provision for easily and accurately adjusting the tool slide both radially and axially relative to the work; and to the provision of means for both yieldingly and positively withdrawing the tools after the turning and squaring operations have been performed.

Our invention further relates to arrangements and combinations of parts which will be hereinafter described and more particularly pointed out in the appended claims.

A preferred form of the invention and a modification thereof are shown in the drawings in which

Fig. 1 is a plan view of the tool slide and support, together with a part of the driving mechanism therefor;

Fig. 2 is a side elevation of the tool slide and support, taken along the line 2—2 in Fig. 1;

Fig. 3 is a rear elevation of the tool slide and support;

Fig. 4 is a sectional elevation of the means for adjusting the cam roll on the tool slide;

Fig. 5 is a detail sectional elevation, taken along the line 5—5 in Fig. 2;

Fig. 6 is a sectional side elevation of the handle for moving the tool slide axially, taken along the line 6—6 in Fig. 5;

Fig. 7 is an end elevation of the driving mechanism, taken along the line 7—7 in Fig. 1 and looking in the direction of the arrow 7 in Fig. 9;

Fig. 8 is an enlarged end elevation of certain parts shown in Fig. 7 but in a different relation;

Fig. 9 is a rear elevation of the driving mechanism, looking in the direction of the arrow 9 in Fig. 7;

Fig. 10 is an enlarged end elevation of certain parts shown in Fig. 7, looking in the direction of the arrow 10 in Fig. 9;

Fig. 11 is a detail rear elevation, looking in the direction of the arrow 11 in Fig. 10;

Fig. 12 is an enlarged sectional plan view, taken along the line 12—12 in Fig. 7;

Fig. 13 is a partial elevation of certain parts, taken substantially along the line 13—13 in Fig. 12;

Fig. 14 is an enlarged elevation of certain parts shown in Fig. 13;

Fig. 15 is a partial enlarged rear elevation, looking in the direction of the arrow 15 in Fig. 13;

Fig. 16 is a partial elevation of a ratchet ring;

Fig. 17 is an end elevation of a modified construction in which front and rear tool slides are operated;

Fig. 18 is a plan view of the parts shown in Fig. 17; and

Fig. 19 is a detail front elevation, looking in the direction of the arrow 19 in Fig. 17.

Referring to Fig. 1, we have shown the work W rotatably mounted upon a head or live center 20 and a tail center 21, these centers being mounted in head and tail stocks not shown and forming no part of our present invention. A portion of the bed which supports the head and tail stocks is shown, however, at 22 and is provided with guide-ways, as shown in Fig. 2, upon which a base support 23 may be clamped by binding screws 24 in any selected position along the guide-way.

A base 25 (Fig. 2) is mounted to slide transversely upon a guide-way 26 formed on the upper surface of the base support 23. A threaded stud 27 (Fig. 5) is rotatably mounted in a bearing in a block 28 firmly secured to the side of the base 25. A flange 29 on the stud 27 prevents outward axial movement of the stud and a pinion 30 is keyed to the stud outside of the block 28 and prevents inward axial movement of the stud.

A handle 31 is rotatably mounted on the ends of the teeth of the pinion 30 (Fig. 6) and is held in position thereon by a washer 110.

32 (Fig. 5). The inner end of the stud 27 is split or slotted as indicated at 33 and the stud is provided with an axial recess tapered at its inner end to receive a rod 34 having a tapered head 35. The outer end of the rod 5 is threaded in the stud 27 and has a screw driver slot by which the tapered rod may be turned to draw it into the stud 27 to adjust the fit of the threaded stud in the base support 23. A nut 36 is threaded on the stud 27 10 and holds the washer 32 in frictional contact with the handle 31.

A rod 37 is mounted to slide longitudinally in the handle 31 and is pointed at its lower end to enter between the teeth of the pinion 30. At its upper end the rod 37 has a head 38 and is surrounded by a spring 39 which normally forces the rod upward out of engagement with the teeth of the pinion 30. The handle 31 is provided with a sliding hand piece or grip 40 which may be pushed downward to cause the rod 37 to engage the teeth of the pinion. 15

When it is desired to adjust the base 25 longitudinally of the work on the base support 23, the stud 27 is turned by the handle 31 to produce the desired adjustment. I have thus provided a simple and convenient ratchet feed for adjustment of the base on 30 its support, axially of the work.

A tool slide 41 (Figs. 1 and 2) is mounted in guideways on the base 25 and is preferably provided with a raised portion 42 (Fig. 2) having one or more T slots or openings 35 43 to receive bolts 44 by which a suitable tool block or base 45 may be secured in position. This tool block 45 is preferably provided with ribs or projections 46 fitting the T slots and aligning the tool block 45 with the tool slide 41. The tool block 45 40 may be slotted at different angles to receive the tools T, as indicated in Fig. 1 and the tool block may also have a threaded flange or lug 47 to receive adjusting screws 48 by 45 which the tools T may be separately adjusted toward the work. Binding screws 49 (Fig. 1) hold the different tools T in adjusted position.

A cam 50 (Fig. 2) mounted on a cam shaft 51 engages a cam roll 52 (Figs. 2 and 4) to force the tool slide 41 toward the work W. The cam roll 52 is rotatably mounted in the end of a plunger or roll carrier 53 (Fig. 4) which is slideable in an opening 54 55 in the tool slide 41. The plunger 53 is slotted or grooved at 56 to receive the reduced end of a stud or screw 57 by which it is held from rotation.

A threaded stud 58 is mounted in a bearing in the front end of the tool slide 41 and is held from axial movement therein by a flange 59 at the inside of the bearing and by a washer 60 and nut 61 on the outer end of the stud. The stud 58 is threaded into the 65 plunger or roll carrier 53 and the roll may

thus be conveniently adjusted relatively to the tool slide 41. By this adjustment, the extreme forward position of the tool T which will be reached during the rotation of the cam 50 may be varied as desired.

The cam shaft 51 is rotatable in bearings 63 (Fig. 1) at the rear end of the base 25 and is intermittently rotated by driving mechanism to be described. A chain 64 is secured at one end to the tool slide 41 and passes rearward over the cam shaft 51, from which point it hangs freely and supports a heavy weight 65 by which the tool slide 41 is drawn rearward and the cam roll 52 is caused to firmly engage the cam 50.

The tool slide is thus yieldingly returned to rearward position after being forced forward by the cam 50. There is a possibility, however, that the tool slide may bind or encounter unusual resistance to its return movement, and accordingly I have provided means for positively withdrawing the tool slide from cutting position. For this purpose, I provide a pin or stud 66 (Fig. 2) mounted in the side of the cam 50 and positioned to engage a hook 67 which is pivoted at 68 on an upward projection 69 of the tool slide 41 and which extends beyond the pivot 68 for engagement by a stop screw 70. As the cam 50 rotates in the direction of the arrow a in Fig. 2, the stud 66 engages the hook 67 as the cam roll 52 passes the point of the cam 50 and such engagement draws the tool slide 41 positively rearward. As the rearward movement is continued, the pin or stud 66 moves downward and is gradually withdrawn from the hook 67, which is limited in its downward movement by the adjusting screw or stop 70. Provision is thus made for positively withdrawing the tool slide after actuation by the cam 50.

In Figs. 17, 18 and 19, I have shown a double support 71 having a tool slide 72 at the rear of the work and a second tool slide 73 in front of the work. The slide 72 is provided with a roll 74 engaged by a cam 75 on a cam shaft 76 as previously described. The front slide 73 is mounted in transverse guide-ways 77 (Fig. 19) and is connected by a depending block 78 and a rod 79 to a link 80 which is pivoted at its rear end to a cam lever 81. The lever 81 is pivoted at its lower end to a downward and rearward projection 82 of the base support 71 and has a cam roll 83 at its upper end engaging a second cam 84 on the cam shaft 76. A chain 85 connects the slide 72 to the usual weight (not shown) for withdrawing the slide from the work. A heavy spring 86 (Fig. 17) may be provided for removing the front slide 73 forward away from the work.

Driving mechanism.

We will now describe the mechanism by

which the cam shaft 51 may be rotated at different speeds and may be started when desired and automatically stopped at the completion of a single revolution. A sprocket 5 chain 90 (Fig. 7) is driven from the lathe spindle or from some other continuously rotating shaft (not shown) and drives a sprocket 91 mounted on a short horizontal shaft 92 (Fig. 9) which is rotatable in bearings in a casing 93, pivoted to swing about the axis of a counter shaft 94 mounted in a bracket 95 fixed to the frame of the lathe. A pinion 96 (Fig. 9) on the sprocket shaft 92 engages a gear 97 on the counter shaft 10 94. A fixed stud 98 (Fig. 7) extends through a slotted projection 99 (Fig. 9) on the casing 93 and is provided with lock nuts 100 and 101 by which the casing 93 may be swung forward or rearward to adjust the tension 15 20 of the sprocket chain 90.

A bevel gear 102 on the counter shaft 94 engages a second bevel gear 103 (Figs. 7 and 8) on a worm shaft 104 mounted in bearings in a bracket or support 105. The 25 shaft 104 has a worm 106 adapted to engage a worm wheel 107 which is freely rotatable upon a shaft 108 (Fig. 12) aligned with the cam shaft 51 and connected thereto by a driving clutch or coupling 109 so constructed 30 as to permit slight relative movements between the shafts 108 and 51. The worm gear 107 forms part of a slow speed drive for the cam shaft 51.

The high speed drive is taken from a 35 vertical shaft 110 (Fig. 7) which is continuously rotated from any suitable drive shaft in the head of the lathe. A bevel gear 111 at the upper end of the shaft 110 engages a bevel pinion 112 on a worm shaft 113. The shaft 113 is mounted in suitable fixed bearings and has a worm 114 meshing with a worm wheel 115 (Fig. 12). The worm wheel 115 is mounted on a short shaft 116 rotatable in a fixed bearing 117 and having a spur gear 118 at its opposite end, meshing with a similar gear 119 which is freely slidable and rotatable upon a sleeve or bushing 120 on the shaft 108.

A clutch disc 121 (Fig. 12) is secured to 50 the face of the gear 119 and a corresponding clutch disc 122 is secured to the adjacent face of a ratchet hub 123 on which is mounted a ratchet ring 124 (Figs. 13 and 16). A pawl 125 (Fig. 14) is mounted in a recessed projection on the side of the worm wheel 107 and is retained therein by a plate 127 (Fig. 15). A spring 128 forces the pawl 125 yieldingly into engagement with the teeth of the ratchet ring 124 but permits the pawl 55 to be forced outward away from the teeth as will be hereinafter described.

The ratchet hub 123 is keyed to the shaft 108 and the ratchet and shaft are normally rotated at relatively slow speed by the worm 60 gear 107, acting through the pawl 125. The

spur gear 119, as previously described, is 65 slideable along the shaft 108 and is freely rotatable thereon. An annular groove 130 in the hub of the gear 119 receives rolls 131 on the arms of a yoke 132 (Fig. 10) mounted 70 on a fixed pivot 133 and having a depending arm 134. A clutch controlling plate 135 (Figs. 10 and 11) is fixed to a projection 136 on the side of the arm 134 and projects into the path of cam plates or dogs 137 75 (Figs. 10 and 12) which are bolted to the periphery of the ratchet hub 123.

When the plate 135 is engaged by a cam or dog 137 on the ratchet hub 123, the yoke 132 is swung outward against the pressure 80 of a spring 138 (Fig. 12) and separates the clutch discs 121 and 122. When the dogs or cam plates 137 pass from engagement with the plate 135, the spring 138 causes the clutch discs 121 and 122 to engage each other 85 and thereby drive the ratchet hub 123 at a relatively high speed, causing the hub 123 to run ahead of the worm wheel 107. This action is made possible by the pawl and ratchet connection between the ratchet hub and worm wheel. The shaft 108 and the connected cam shaft 51 will thus be rotated at relatively high speed, so long as the clutch discs 121 and 122 are engaged.

Stopping mechanism.

We will now describe the mechanism through which the rotation of the cam shaft is stopped after one revolution and through which it may be manually stopped at any desired point. The casing 105 (Fig. 8) supporting the worm shaft 104 is provided with a tooth or lug 140 positioned for engagement by a latch 141 mounted on a fixed pivot 142. An arm 143 extends forward from the latch 141 in position for engagement by a strip or stud 144 (Fig. 10) on the periphery of the ratchet hub 123. When the strip 144 engages the arm 143, the latch 141 will be 100 swung outwardly, releasing the lug 140 and allowing the casing 105 to drop and disengage the worm 106 from the worm wheel 107. The continuous low speed drive of the cam shaft will thus be interrupted after a 105 single revolution of the shaft.

For releasing the latch manually, we provide a stopping lever 150 (Fig. 7) pivoted at 151 and actuating a stop rod 152. A collar 153 on the rod 152 is positioned to engage a pin 154 (Fig. 8) on the latch arm 143. The handle 150 may thus be used to depress the latch arm and release the latch 141. A spring 155 yieldingly moves the latch towards engaging position. The weight of the handle 150 holds the rod 152 120 in normally raised position and the upward movement of the rod 152 is limited by check nuts 156 (Fig. 8) on the lower end of the rod.

In order to stop the cam shaft 51 man- 130

ually, it is also essential that the high speed drive shall be simultaneously disconnected and for this purpose a cam block 160 (Figs. 10 and 11) is fixed to the upper side of the 5 worm shaft casing 105, as by a screw 161, and is adapted to engage the beveled lower end 162 of the yoke arm 134. As the casing 105 is released by the latch 141 and drops downward to inoperative position, the cam 10 block 160 engages the end 162 of the yoke arm and moves the same from the dotted line to the full line position shown in Fig. 11, thus separating the clutch discs 121 and 122 and disconnecting the high speed drive. 15 A stop 165 (Fig. 8) limits downward movement of the casing 105.

Having thus fully described our invention and the construction thereof, it is believed that the general operation of the machine 20 will be easily apparent. The hand lever 150 is used both for starting the machine and also for manually stopping the machine if desired. In starting the machine, the lever 150 is depressed, causing the check nuts 156 25 to act against the worm casing 105, swinging the same upward so that the worm wheel will be engaged. The casing is secured in raised position by the latch 141. The worm wheel 107 thereafter makes one 30 revolution, during a portion of which the high speed drive is released from the plates or dogs 137 and advances the lathe tool toward operative position or withdraws the same rapidly from such position. During 35 the turning operation, the high speed drive is disconnected by the plates or dogs 137 and the cam shaft is driven at the desired slow speed. At the completion of one revolution, the trip 144 releases the latch 141 40 and the cam shaft 151 comes to rest until again started by the operator. In the construction shown in Figs. 17, 18 and 19, the cam shafts operate two tool slides or carriages simultaneously in opposite directions. 45 Having thus described our invention and the advantages thereof, we do not wish to be limited to the details herein disclosed otherwise than as set forth in the claims, but what we claim is:—

50 1. In a lathe, a back squaring attachment comprising a base, a tool slide mounted for movement transversely of the lathe on said base, an actuating cam for said slide, means to yieldingly withdraw said slide, means to positively withdraw said slide, said positive withdrawing means becoming positively engaged if the normal yielding withdrawal of said slide is retarded, and means to automatically disengage said positive withdrawing 55 means as said slide reaches a predetermined withdrawn position.

60 2. In a lathe, a back squaring attachment comprising a base, a tool slide mounted for movement transversely of the lathe on said base, an actuating cam for said slide, means

to yieldingly withdraw said slide, a stud on said cam and a hook on said slide engaged by said stud to positively withdraw said slide.

65 3. In a lathe, a back squaring attachment comprising a base support, a base, a tool slide mounted on said base, and means to adjust said base on said support, said means comprising a stud having a bearing in said base and threaded in said support, a pinion fixed to said stud, a handle pivoted on said pinion, a plunger in said handle, and a handle grip depressible to engage said plunger with said pinion, whereby said pinion may be moved angularly.

70 4. In a lathe, a tool slide movable transversely of said lathe toward and from the axis of the work, an actuating shaft connected to move said slide transversely, means to turn said shaft successively slowly and rapidly during a single revolution thereof, and means to stop said shaft after said single revolution is completed and while the work driving mechanism of the lathe continues in operation.

75 5. In a lathe, in combination, a tool slide, mechanism to move said slide transversely of said lathe toward and from the axis of the work, a high speed drive for said mechanism, a low speed drive for said mechanism, automatic means to shift said mechanism from one drive to the other at predetermined points in the operation of the lathe, and means to stop said mechanism after a single reciprocation of said slide and while the work driving mechanism of the lathe continues in operation.

80 6. In a lathe, a tool slide movable transversely of said lathe, an actuating shaft connected to move said slide toward and from the axis of the work, a relatively slow speed drive for turning said shaft, a relatively high speed drive for turning said shaft, and manual means to disconnect both said high and said low speed drives and to stop the 85 shaft at any desired point while the work driving mechanism of the shaft continues in operation.

85 7. In a lathe, a tool slide movable transversely of said lathe, an actuating shaft connected to reciprocate said slide toward and from the axis of the work, means to turn said shaft successively slowly and rapidly during a single revolution thereof, manual means to start said shaft in rotation and 90 automatic means to stop said shaft at the end of a single reciprocation of said slide and while the work driving mechanism of the lathe continues in operation.

95 8. In a lathe, a tool slide movable transversely of said lathe, an actuating shaft connected to move said slide, means to turn said shaft both slowly and rapidly during a single revolution, manual means to start said shaft in rotation and to stop the move- 100

ment of said shaft at any desired point while the work driving mechanism of the lathe continues in operation, and automatic means to stop said shaft at the end of a 5 single revolution.

9. In a lathe, a tool slide movable transversely of said lathe, an actuating shaft connected to move said slide, a slow moving worm wheel loose on said shaft, a hub fixed 10 to said shaft, a pawl and ratchet connection between said worm wheel and said hub, a second driving member loose on said shaft and rotated at relatively high speed, and a 15 clutch connection between said driving member and said fixed hub, said hub over-running said slow running worm wheel when connected to said high speed driving member.

10. In a lathe, a tool slide movable transversely of said lathe, an actuating shaft connected to move said slide, a hub fixed to said shaft, a relatively slow speed driving member in continuous driving relation to said hub, a relatively high speed driving member 25 normally free from said hub, and automatic means to connect said high speed member to said hub during certain predetermined parts of a revolution of said shaft, thereby causing said hub to over-run its driving engagement with said slow speed driving member.

11. In a lathe, a tool slide movable transversely of said lathe, an actuating shaft connected to move said slide, a relatively slow speed worm wheel to drive said shaft, a relatively high speed worm wheel to drive said shaft, a continuously rotated worm and worm shaft for each worm wheel, a pivoted bearing casing for the slow speed worm 35 shaft, a clutch connection between said high speed worm wheel and said actuating shaft, and means to release said casing to disengage said slow speed worm and to simultaneously disengage said clutch in the high 40 speed drive.

12. In a lathe, a tool slide movable transversely of said lathe, an actuating shaft con-

nected to move said slide, a relatively slow speed worm wheel to drive said shaft, a relatively high speed worm wheel to drive said 50 shaft, a continuously rotated worm and worm shaft for each worm wheel, a pivoted bearing casing for the slow speed worm shaft, a clutch connection between said high speed worm wheel and said actuating shaft, 55 a latch for said casing, means to release said latch and thereby disengage said slow speed worm, and a cam on said casing effective to simultaneously disengage said clutch connection. 60

13. In a lathe, a tool slide movable transversely of said lathe, an actuating shaft connected to move said slide, a relatively slow speed worm wheel to drive said shaft, a relatively high speed worm wheel to drive said 65 shaft, a continuously rotated worm and worm shaft for each worm wheel, a pivoted bearing casing for the slow speed worm shaft, a clutch connection between said high speed worm wheel and said actuating shaft, 70 a latch for said casing, automatic and manual means to release said latch, and automatic means to disengage said clutch connection. 75

14. In a lathe, a tool slide movable transversely of said lathe, an actuating shaft connected to move said slide, a relatively slow speed worm wheel to drive said shaft, a relatively high speed worm wheel to drive said 80 shaft, a continuously rotated worm and worm shaft for each worm wheel, a pivoted bearing casing for the slow speed worm shaft, a clutch connection between said high speed worm wheel and said actuating shaft, a manually operated handle connected for movement in one direction to raise and latch 85 said casing and in the opposite direction to unlatch and release said casing, and means operated by said casing to release said clutch connection. 90

In testimony whereof we have hereunto affixed our signatures.

NATHANIEL KING.
RICHARD A. ASHTON.
